UNITED STATES PATENT OFFICE.

JOHN KABACI, OF WYANO, PENNSYLVANIA, ASSIGNOR OF ONE-HALF TO CHARLES HESS, OF WYANO, PENNSYLVANIA.

LOCKING DEVICE FOR MAIL POUCHES OR BAGS.

1,351,388.

Specification of Letters Patent. Patented Aug. 31, 1920.

Application filed December 9, 1919. Serial No. 343,623.

To all whom it may concern:

Be it known that I, JOHN KABACI, a citizen of the United States, residing at Wyano, in the county of Westmoreland and State of Pennsylvania, have invented certain new and useful Improvements in Locking Devices for Mail Pouches or Bags, of which the following is a specification, reference being had therein to the accompanying drawings.

10 This invention relates to a locking device for mail pouches or bags, and it has for its object the construction of a simple and efficient device that will close the mouth of the bag, lock the bag in its closed position, and 15 at the same time afford an excellent handle by means of which the bag can be lifted or conveyed at the will of the operator.

With this and other objects in view, the invention comprises certain other novel combinations, constructions and arrangements of parts as will be hereinafter specifically described, illustrated in the accompanying drawings, and more particularly pointed out in the appended claims.

25 In the drawings:

Figure 1 is a fragmentary perspective view of a mail pouch, showing my improved device or apparatus applied thereto.

Fig. 2 is a fragmentary perspective view 30 of a mail pouch, showing the same closed by my device or apparatus, with a portion of the device in position to be used as a handle.

Fig. 3 is a front view of the lock, showing the ends of the loop therein and in section.

35 Fig. 4 is an interior view in elevation of the lock with the cover removed.

Fig. 5 is a section taken on line 5—5, Fig. 4 and looking in the direction of the arrows.

Fig. 6 is a perspective view of the primary 40 plate of the lock.

Fig. 7 is a perspective view of one of the sliding bolts.

Fig. 8 is a fragmentary perspective view 45 of the device, showing particularly the catch device thereto.

Fig. 9 is a fragmentary view of the device showing particularly the head plate and hook attached to the ends of the loop.

Fig. 10 is a perspective view of the key 50 receiving plate.

Referring to the drawings by numerals, 1 designates the bag or pouch which is provided on its sides or open end with eyelets 2. Through these eyelets is threaded a loop 3.

55 This loop is provided in its outer face with

pockets 4 into which pockets extend the reduced ends 5 of the sliding bolts 6. The ends 7 of the loop are fastened in the ends of the head plate 8, and integral with the central portion of the outer face of the plate 60 is a hook 9.

The hook 9 is adapted to ride over the beveled portion 10 of the sliding bolt 11, carried within the casing 12 of the catch device 13 (Figs. 1 and 8). The casing 12 is fastened 65 to a horizontal plate 14, which plate is provided with a transverse groove 15; the sliding bolt 11 has its beveled end 10 normally overhanging the groove 15 so that the hook 9 can project down into the groove and be 70 retained therein by bolt 11 when the loop has been drawn tightly through the lock 16, and the outer end of the loop is to be used as a handle, Fig. 2.

The bolt 11 is drawn rearwardly into the 75 casing 12 by means of handle 17, which handle is pivotally connected at 18 to the pin 19, which pin 19 is fastened at its inner end to the bolt 11, Fig. 8. The plate 14 is secured to the top of the inverted U-shaped 80 frame 20, which frame has its outer portion or leg 21 fastened against the outer face of loop 3, and its inner portion or leg 22 fastened against the inner face of the bag or pouch 1. By reason of this catch device 13 being assembled with the pouch and loop, 1 provide a very simple and efficient device 85 for holding the loose end of the loop when it has been drawn tight for closing the mouth of the bag, enabling an efficient handle to be readily provided for lifting or conveying the pouch.

The lock 16 through which the loop 3 extends comprises a casing 23 having a front plate 24 and a rear plate 25. A keyhole 95 26 is formed in the front plate, and over the portion of plate 24 in which the keyhole 26 is formed is a key-receiving plate 27, which plate has a sleeve 28 that extends into plate 24 so that the plate 27 will be secured 100 in position within the casing 23. Fastened to the sides of the plate 27, near opposite ends are apertured lugs 29, and pivotally secured to these lugs 29, at their inner ends, are links 30. Extending from each sliding bolt 6 is a rigid rod 31, and each rod is provided at its outer end with an eye 32, and in the eyes 32 of the rods 31 are positioned or fastened the outer ends of the links 30. A coil spring 33 is between the inner ends of 105 110

the bolts 6. The primary plate 34 comprises parallel sides 35 and 36, and between the sides is an elongated slot 37, and extending into the slot 37 near its ends from the sides 35 and 36 are pairs of lugs 38, which lugs form, at the ends of the slot 37, pockets or guideways through which the loop 3 extends; it is to be noted that plate 34 is provided with pockets at its ends for receiving the loop, by reason of the slot and lug structure of the plate, just described. The side portion 36 of plate 34 is cutaway on its inner face, at 39, for permitting the rods 31 to slide within the plate, and also acting as a guide for these rods during the movement of the bolts 6. Auxiliary plates 40 are secured to the primary plate between one face thereof and the rear plate 25 of the casing 23, which auxiliary transversely-positioned plates 40 act as a guide to prevent the bolts 6 from being displaced off the primary plate 34.

The operation of the device or apparatus is as follows: When the parts are in the position shown in Fig. 1 all the operator needs to do is to pull upon the head plate 8, drawing the loop outwardly through the lock 16, and when the mouth of the pouch has been closed (Fig. 2), causing the pockets 4 in the side of the loop to register with the reduced ends 5 of the bolts 6, said reduced ends will enter the pockets 4 (Fig. 4), locking the loop in its closed position upon the mouth of the pouch. Then the operator can bend the extended ends of the loop over so as to cause the hook 9 to engage the sliding bolt 11, thereby locking the head plate upon the catch device 13, producing an efficient handle for handling or conveying the bag or pouch. Upon the operator pulling on the handle 17, bolt 11 will be drawn within the casing 12 releasing the head 8, and then by inserting the key into the aperture 26, key-receiving plate 27 can be pivoted, causing the bolts 6 to be drawn together, compressing spring 33, and thereby removing the reduced ends 5 out of the pockets 4 of the loop, permitting the loop to be run through the lock 16 for opening the bag or pouch, Fig. 1.

While I have described the preferred embodiment of my invention in the foregoing description, and have illustrated the same in the accompanying drawings, certain minor alterations or changes may appear to one skilled in the art to which this invention relates, during the extensive manufacture of this invention, and I therefore reserve the right to make such minor alterations or changes as shall fairly fall within the scope of the appended claims.

What I claim is:

1. In an apparatus of the class described, the combination with a pouch, of a lock secured to said pouch, a catch device secured

to said pouch, and a loop on said pouch and extending through said lock, whereby the loop may be drawn through the lock for closing the pouch and then fastened to the catch device for producing a handle on the pouch. 70

2. In an apparatus of the class described, the combination with a pouch, of a lock secured to the side of said pouch, said lock comprising a casing, a primary plate secured within said casing, said primary plate provided with sides and with an elongated slot in its center, said sides provided near the ends of the slot with pairs of inwardly-extending lugs, the extreme ends of the slot and the lugs constituting loop receiving-pockets, a loop extending around the pouch and through the lock and being positioned in the pockets at the ends of the plate, said loop provided in its outer face with bolt-receiving pockets, spring pressed bolts in the elongated slot of the primary plate and provided with reduced ends extending into the pockets at the ends of the primary plate and also into the pockets formed in the sides of the loop, for holding the loop in an adjusted position, auxiliary plates on one side of the primary plate for holding the bolts in position, one side of said primary plate provided with a cutaway portion, rods on the sliding bolts and positioned in the cutaway portion of the primary plate, a key-receiving plate provided with a sleeve, said sleeve extending into one side of the casing, said key-receiving plate provided with apertured lugs, and links secured at their inner ends in said lugs and at their outer ends pivotally secured to the rods carried by the bolts. 90

3. In an apparatus of the class described, the combination with a pouch, of a loop on said pouch, locking means upon the pouch for retaining the loop in a closed position, a catch device on the pouch, said catch device comprising an inverted U-shaped frame, a plate on said frame, a casing on said plate, a spring pressed bolt projecting from said casing, and a hook formed on the outer end of the loop and being adapted to engage the spring pressed bolt of the catch device for permitting the outer loose end of the loop to constitute a handle when the loop is in a 115 closed position upon the pouch.

4. In an apparatus of the class described, the combination with a pouch, a locking device on said pouch, of a loop surrounding the pouch and extending through and beyond the locking device, a hook formed upon the outer end of said loop, and a locking device for holding the hook formed upon the pouch and having a portion secured to the inner face of the pouch and another portion 120 secured to the outer face of the loop.

5. In an apparatus of the class described, the combination with a pouch, of a slotted lock secured to the side of the pouch, a loop surrounding the pouch and extending 130

through the slots of the lock, and extended ends of the loop provided with hook means, a catch device provided with an inverted U-shaped frame and with locking means fastened to the pouch and the loop, and said hook means adapted to be engaged and be held by the locking means of the

catch device for utilizing the loose or outer end of the loop as a handle when the loop is held in a closed position by the lock on the 10 side of the pouch.

In testimony whereof I hereunto affix my signature.

JOHN KABACI.
